UNITED STATES PATENT OFFICE

154,483

DESIGN FOR A TOOTHBRUSH AND GLASS HOLDER

Jerome A. Hipsley, Albany, Calif.

Application October 10, 1947, Serial No. 141,850

Term of patent 3½ years

(Cl. D4—3)

To all whom it may concern:

Be it known that I, Jerome A. Hipsley, a citizen of the United States, residing at Albany, in the county of Alameda and State of California, have invented a new, original, and ornamental Design for a Toothbrush and Glass Holder, of which the following is a specification, reference being had to the accompanying drawing, forming part thereof.

Figure 1 is a top side perspective view of a toothbrush and glass holder, showing my new design, and

Figure 2 is an underside perspective view thereof.

I claim:

The ornamental design for a toothbrush and glass holder, as shown.

JEROME A. HIPSLEY.
